(57) **CLAIM**

The ornamental design for a camping trailer as shown and described.

DESCRIPTION

1. Camping trailer

1.1 : Top, front, right-side perspective view

1.2 : Top, back, left-side perspective view

1.3 : Front

1.4 : Back

1.5 : Left

1.6 : Right

1.7 : Top

1.8 : Bottom

1.9 : Reference view

1.10 : Reference view

1.11 : Reference view

1.12 : Reference view

1.13 : Reference view

The characteristic features of the design lie in the shape; reproduction 1.9 shows the door opened in use; reproductions 1.10 to 1.12 illustrate a state of use; reproduction 1.13 is an enlarged view of the encircled portion in reproduction 1.12; the broken lines shown in reproductions 1.1 to 1.8 depict portions of the camping trailer that form no part of the claimed design; other broken lines shown in reproductions 1.9 to 1.13 depict environmental structure and form no part of the claimed design; the shading lines are used to show the surface of the claimed design and do not represent its surface ornamentation.
